CLAIM

The ornamental design for a cradle for mobile terminal, as shown and described.

DESCRIPTION

FIG. 1 is a perspective view of a cradle for mobile terminal;
FIG. 2 is a front elevation view thereof;
FIG. 3 is a rear elevation view thereof;
FIG. 4 is a side view thereof;
FIG. 5 is a top plan view thereof; and,
FIG. 6 is a bottom plan view thereof.

The portions of the cradle for mobile terminal shown in broken lines form no part of the claimed design.
